HOPPER CONSTRUCTION

Karl M. Hamilton, Chicago, Ill., assignor to The Bettendorf Company, Bettendorf, Iowa, a corporation of Iowa

Application September 11, 1937, Serial No. 163,411

9 Claims. (Cl. 105—251)

This invention relates to railway hopper cars, and in particular to an improved hopper construction.

An object of this invention is to provide a railway car hopper construction composed of parts which may be formed separately, and assembled.

A further object of this invention is to provide an improved hopper construction which will be easy and economical to manufacture.

Another object of this invention is to provide a hopper construction in which the parts may be readily cast separately and secured together to form the hopper.

Other objects of this invention will be apparent from the following detailed description, accompanied by the drawings illustrating a hopper of the type contemplated in the present invention, in which

Figure 1 is a perspective view of a hopper embodying the invention;

Fig. 2 is a side elevation showing the hopper in position attached to the underframe of a railway car;

Fig. 3 is a fragmental section taken substantially on line 3—3 of Fig. 2, showing the connection of two metal parts of the hopper;

Fig. 4 is a fragmental section taken substantially on line 4—4 of Fig. 2;

Fig. 5 is a fragmental sectional view taken substantially on line 5—5 of Fig. 2;

Fig. 6 is a transverse sectional view taken substantially on the line 6—6 of Fig. 2, showing the hopper in rear elevation;

Fig. 7 is a fragmental sectional view taken substantially on line 7—7 of Fig. 6 showing the relation between a side plate, the floor plate, and the lower cross rail;

Fig. 8 is a fragmental sectional view taken substantially on line 8—8 of Fig. 6 illustrating the upper end of the hopper floor plate and its connection to the car.

Referring to the accompanying drawings, which illustrate the invention, it will be seen that the hopper is of such formation that it may be secured to a standard hopper car. The hopper comprises side plates 1 and 2, upper and lower cross rails 3 and 4, and a floor plate 5, which are separately formed and secured together to form a hopper unit. The side plate 1 of the hopper is substantially triangular in shape and it is provided with recesses 6 and 7 at the upper and lower corners at the mouth end of the hopper. Similarly, the side plate 2 is triangular in shape and has corresponding recessed portions 6' and 7'. The upper cross rail 3 is provided

with end flanges 8 which mate with the recesses 6, 6' of the side plates 1, 2. The lower cross rail 4 is similarly provided with end flanges 9 to mate with the recesses 1, 1' of the side plates. A chute floor plate 5 is supported on inwardly extending flanges 10 of the side plates 1 and 2, and at its lower end overlaps and extends partially across the inner portion of the cross rail 4. The central portion of the lower cross rail 4 between the end flanges thereof forms the chute lip of the hopper.

The side plate 1 is provided with a downwardly projecting flange 11 which is fastened to a center sill 12 of a railway car by rivets or other suitable means, as shown in Fig. 2. The outer side plate 2 of the hopper is provided along its upper edge with an outwardly projecting flange 13 which may be secured to the side frame of a car by any suitable means, such as riveting, welding or the like. The flange 13 may be provided with strengthening ribs. Preferably, it is secured to the structural member 14 carried by the side wall of the car by rivets, as shown in Fig. 6.

The cross rail 3 may be united to the side plates 1 and 2 through the medium of the flanges 8, in any suitable manner, preferably by welding along contiguous edges. As shown in Fig. 3, the side plates 1 and 2 may be provided with integral lips 15. These lips 15 are on the outer sides of the plates 1 and 2 and are disposed along the edges of the recesses 6, 6', projecting beyond the edges. The flanges 8, of the cross rail 3 mate with the recesses 6, 6', abutting the edges of the side plates and underlying the lips 15. The flanges 8 may be permanently united to the side plates by welding the contiguous edge portions of the side plates thereto.

The upper cross rail 3 is provided at its inner end with a downwardly extending flange 16 for attachment to the center sill of the railway car. Flange 16 is preferably formed with apertures so that it may be riveted to securely hold it to the car frame. At the outer end the cross rail 3 is provided with an outwardly extending flange 17 which is in alignment with the outwardly projecting flange 13 of the side plate 2. The flange 17 is preferably provided with apertures so that it may be riveted and securely fastened to the member 14 of the car. The central portion of the cross rail 3 between the end flanges 8 is angularly shaped in cross section and is provided with a plurality of hinge lugs 18 which are apertured to receive hinge pins to hold the mating hinge lugs of a suitable door (not shown). The cross rail 3 extends upwardly and forwardly toward

the floor of the car and is provided at its upper edge with a notch 19 which is formed to receive a car floor plate 20. The floor plate 20 is received in the notch 19, thereby providing a flush surface 5 for the discharge of material from the car.

The lower cross rail 4 is shown having a flat central portion with upturned end flanges 9 adapted to be received in the recesses 7 and 7' of the side plates 1 and 2 respectively. The lower cross rail 4 may be fastened to the side plates in a manner similar to the fastening of the upper cross rail 3. As shown in Fig. 5, the flanges 9 of the cross rail 4 are positioned in the recesses 7 and 7' abutting the edges of the side plates and underlying lips 21 which are on the outer sides of the plates 1 and 2 projecting beyond the edges of the recesses 7, 7'. Flanges 9 of the cross rail may be permanently united to the side plates by welding to the contiguous edge portions of the 20 side plates. The central portion of the cross rail 4 between the end flanges 9 forms a chute lip which may be provided with a suitable boss 22 for the attachment of a latch mechanism (not shown).

25 The inturned flanges 10 are disposed along substantially the length of the lower inclined edge of the side plates 1 and 2. The flat floor plate 5 is supported thereon and overlies a portion of the chute lip of the lower cross rail 4, as shown 30 in Fig. 7.

Fig. 8 shows the method of joining the floor plate 5 at its upper end to the car floor plate 23 and the side plates 1 and 2. At the upper end of the inwardly extending flanges 10 of the side plates 1 and 2 there is a downwardly turned end portion 24. To this is attached by riveting or other suitable means an angle bar 25. This angle bar 25 supports both the floor plate 5 and the car floor plate 23. With the floor plate 23 and the 40 floor plate 5 in abutment, loose material may be readily discharged from the car through the hopper.

The end portions of the side plates terminate at their discharge ends in flanges 26 which are 45 preferably offset inwardly. Likewise the end flanges 8 and 9 of the cross rails 3 and 4 terminate at their discharge ends in inwardly offset flanges, substantially in alignment with the flanges 26 of the side plates. An outwardly extending flange 27 of the upper cross rail 3, together with the flanges 26 of the side plates and portion 28 of the lower cross rail 4 define a four-sided hopper opening.

In the manufacture of this hopper the parts 55 are formed separately and assembled, preferably by the means of a suitable jig or holding device. When the separate pieces are in an assembled position they may be securely fastened together by welding or riveting or other suitable means. The side plates 1 and 2 and the upper and lower 60 cross rails 3 and 4 are preferably cast and welded together while the floor plate 5 may be either cast or a rolled section.

The parts of this hopper can be readily made, 65 as by casting in molds and secured together as disclosed herein, whereby a simple and strong hopper construction, which will resist corrosion, is obtained at a relatively low cost. Also, if a part of the hopper should be broken in service it may 70 be replaced.

It is to be understood that details of the construction shown and described herein are for the 75 purposes of illustration and explanation and that such details may be varied without departing from the invention.

What I claim is:

1. In a railway car hopper construction, two substantially triangular side plates, each being recessed at the upper and lower corners of the discharge end, upper and lower cross rails having end flanges fitting in the recessed corners of the side plates and secured thereto, and a floor plate supported by and secured to the side plates and overlying the lower cross rail. 5

2. In a railway car hopper construction, two 10 cast, substantially triangular side plates, each being recessed at the upper and lower corners of the discharge end thereof, upper and lower cast cross rails having end flanges fitting in the recessed corners of the side plates, and a floor 15 plate supported by the side plates and overlying the lower cross rail, said parts being firmly secured together to form a hopper for attachment to a railway car.

3. In a railway car hopper construction, two 20 substantially triangular side plates, each recessed at the upper and lower corners of the discharge end thereof, upper and lower cross rails having end flanges fitting in the recessed corners of the side plates, lips formed on the side plates and 25 overlying said end flanges of the upper and lower cross rails, said lips and flanges being welded together, and a floor plate carried by the side plates and overlying the lower cross rail.

4. In a railway car hopper construction, two 30 cast, substantially triangular side plates, each being recessed at the upper and lower corners of the discharge end thereof, upper and lower cast cross rails having end flanges fitting in the recessed corners of the side plates, said side plates 35 having inwardly extending flanges along their bottom edges, and a floor plate supported by the inwardly extending flanges on the side plates and overlying the lower cross rail, said parts being firmly secured together to form a hopper for attachment to a railway car. 40

5. In a railway car hopper construction, two substantially triangular side plates, each being recessed at the upper and lower corners of the discharge end, upper and lower cross rails having end flanges fitting in the recessed corners of the side plates and secured thereto, and a floor plate supported by and secured to the side plates and overlying the lower cross rail, said upper cross rail provided with flanges to secure it to a 45 center sill and also to a structural member carried by the side wall of the car. 50

6. In a railway car hopper construction, two substantially triangular side plates, each being recessed at the upper and lower corners of the discharge end, upper and lower cross rails having end flanges fitting in the recessed corners of the side plates and secured thereto, and a floor plate supported by and secured to the side plates and overlying the lower cross rail, said upper cross rail having flanges for attachment to the car and notched to receive the lower end of a car floor plate. 65

7. In a railway car hopper construction, substantially triangular outer and inner side plates, each being recessed at the upper and lower corners of the discharge end, upper and lower cross rails having end flanges fitting in the recessed corners of the side plates, and a floor plate carried by the side plates, said outer side plate having an outwardly projecting horizontal flange, and said upper cross rail having a horizontal flange in alignment with the flange of the side plate for attachment to a structural member carried by a side wall of the car. 70

8. In a railway car hopper construction, two substantially triangular side plates, each being recessed at the upper and lower corners of the discharge end, upper and lower cross rails having end flanges fitting in the recessed corners of the side plates and secured thereto, and a floor plate supported by and secured to the side plates and overlying the lower cross rail, the end portions of the side plates and of the upper and lower cross rails at the discharge end of the hopper terminating in offset flanges disposed in alignment to define a hopper opening.
- 5 9. In a railway car hopper construction, two

substantially triangular side plates, each being recessed at the upper and lower corners of the discharge end, upper and lower cross rails having end flanges fitting in the recessed corners of the side plates and secured thereto, and a floor plate 5 supported by and secured to the side plates and overlying the lower cross rail, said side plates terminating in flanges at their discharge ends, the end flanges of the upper cross rail terminating at their discharge ends in flanges disposed in 10 alignment with the said flanges of the side plates to define the sides of the hopper opening.

KARL M. HAMILTON.
